UNITED STATES PATENT OFFICE.

ALBERT A. FOURNIER, OF OTTAWA, ONTARIO, CANADA.

SOFT CUFF.

Application filed September 4, 1923. Serial No. 660,895.

To all whom it may concern:

Be it known that I, ALBERT A. FOURNIER, a citizen of the Dominion of Canada, residing at Ottawa, in the county of Carleton, Province of Ontario, Dominion of Canada, have invented certain new and useful Improvements in Soft Cuffs, of which the following is a specification.

This invention relates to certain new and useful improvements in soft cuffs.

The present invention has for its objects among others to provide a novel form of soft cuff, as a separate article of manufacture, not designed to be permanently attached to the sleeve of a shirt, but separate and detachable therefrom, and designed to be used with either rolled edge, or wearing edge, exposed to view.

It has for a further object to provide a soft cuff having its edges rolled so as to give the semblance or appearance of the ordinary doubled soft cuff, at the wearing edge one that can be easily washed and having provision for the insertion of a blade or blades or the like at the edges so that the cuff may be kept in its flattened condition when drying after being washed. To this end I form the cuff of material in tubular form flattened with the opposite wearing edges rolled and seamless, the ends being turned in and hemmed or otherwise secured to prevent raw edges, and the ends of the cuff open and unstitched, the opposite faces of the cuff being held in relative position by means passed through the same intermediate the rolled edges, button holes being provided in the ends of the cuff, the stitches of which may serve to retain said opposed faces in fixed relation to each other. This connection, however, does not effect the rolled edges of opposite wearing edges of the cuff, but does prevent freedom of movement of the material of the cuff so that the same cannot be rolled or revolved to bring other portions thereof into position to form the edge when the one portion has become worn, or soiled.

Broadly stated, therefore, the present invention embodies a soft cuff formed of fabric with the opposite wearing edges rolled and unrestricted as to such rolling movement at the edges, the material of which the cuff is formed being united between such rolled edges, the cuff provided adja-

cent the ends with button-holes, the opposed faces of the material being secured together only by the stitches of the button-holes, or stitches or other means adjacent thereto, leaving the end portions open or unattached except for such stitches, thus permitting the desired rolling effect at the wearing edges, but restricting such movement.

Other objects and advantages of the invention will hereinafter appear, and the novel features thereof will be specifically defined by the appended claims.

The invention, as above outlined, is capable of embodiment in a variety of forms, some of which are herein shown by way of illustration.

The invention, in such forms, is clearly illustrated in the accompanying drawings, which, with the numerals of reference marked, thereon, form a part of this specification, and in which

Figure 1 is a perspective view showing one of my cuffs as applied to a shirt sleeve.

Figure 2 is a perspective view of the cuff complete partly broken away.

Figure 3 is an enlarged section as on the line 3—3 of Figure 2.

Figure 4 is an enlarged section as on the line 4—4 of Figure 2.

Figure 5 is a perspective view of another embodiment of the invention.

Figure 6 is an enlarged section as on the line 6—6 of Figure 5.

Figure 7 is an enlarged section as on the line 7—7 of Figure 5.

Figure 8 is a perspective view of another form of embodiment of the invention.

Figure 9 is an enlarged section as on the line 9—9 of Figure 8.

Like numerals of reference indicate like parts throughout the several views.

In carrying out my invention I may make the cuffs in the exact length required, or, the same may be made in long tubular lengths, whereby the sewing can be accomplished quicker, as it does not require so many short stops, and the length of tubing can then be cut into the proper cuff lengths. Whichever way the tubing is formed, however, the resultant cuff is the same.

As shown in Figures 1, 2, 3 and 4 the tube is made of a single piece of material having its edges folded or rolled to form the wear,

ing edges 1, 1, the abutting edges 2—2 of the material being sewn together as at 3, 3, see Figure 2, where broken away, to form a seam, and then the tube is turned inside out, 5 bringing the seam inside the tube where it is concealed. The ends 4 of the material of the tube are then turned in as seen in Figure 4, and secured in such turned-in position by stitches 5, as seen in said Figure 4; see also 10 Figures 1 and 2. These stitches, however, do not unite the opposite faces of the material of the cuffs but they are left free and disconnected except as will be hereinafter described.

15 After the tube has been turned, as just described, and the ends inturned and stitched to prevent them from raveling and to give a finished appearance to the cuff, button-holes 6 are formed at the ends of the cuff.

20 As seen in Figures 3 and 4 the stitches of the button holes extend through opposite faces of the material and thus serve to retain the same in their fixed relation yet allowing of giving the rolling effect at the 25 wearing edges, the material of the cuff being unstitched at or adjacent such edges, as seen clearly in Figure 3. In the completed cuff, the seam being concealed within the cuff, the material is substantially flush at the junction of the edges, so that the seam is 30 hardly observable in the completed cuff.

35 The material of which the cuff is formed may be of one or more plies as may be desired.

40 While in Figure 2 I have shown the button holes as disposed in alignment with the line of stitching as this obviates the unnecessary cutting of the material, it is evident that the same effect in securing the opposed faces of the material together would be accomplished if the button holes were not so relatively placed.

45 Sometimes the cuff may be stiffened by a lining or other stiffening member, as when the material is silk or some other comparatively flimsy nature. The completed cuff is laundered in a flat condition similar to that seen in Figure 2, and is applied as seen 50 in Figure 1. When the wearing edge becomes soiled the cuff is detached from the shirt sleeve and turned edge for edge, bringing the other edge into wearing position, as will be readily understood.

55 In some instances, as for instance, where the material is silk, or some other expensive material, in order that the cost of the cuff may be somewhat reduced I may make the same of two pieces of material, as seen in 60 Figures 5, 6 and 7, the same being of unequal widths, the larger portion 7 being of the same material of the shirt, and rolled at its opposite edges as seen at 8 to form the folded or rolled wearing edges, the longitudinal edges of this piece being folded in-

wardly toward each other and overlapping the main portion, which latter forms the exposed portion of the cuff in use, the narrower portion 9 having its edges stitched to the adjacent edges of the portion 7 to form 70 the seams 10 and 11 as seen in Figure 5, the tube then being turned inside out, the same as in the form above described, the seams then being concealed within the cuff, as seen in Figures 5 and 7, the outer faces of the two pieces being flush as seen in Figures 5 and 7. The ends of the two pieces are then turned in as seen at 12 and stitched as at 13 to prevent raveling and to give a finished 75 appearance to the cuff, the opposed faces of the material not being united by such stitches. Button holes 14 are then formed in the ends of the cuff, the stitches thereof uniting the opposite faces of the cuff, as seen in Fig. 6.

80 The same generic features above outlined are present in the construction of cuff shown in Figure 8 and 9, wherein I employ two pieces of material 15 and 16, of equal widths, having their adjacent edges stitched together 85 as shown at 17 and 18, the tubular blank being the same as in the other forms with the exception that each piece has an edge folded to form a rolling or folded wearing edge, 90 each piece having one edge secured to the unfolded edge of the other piece as seen clearly in Figure 8, so that each face of the cuff is composed of a major portion of one piece and a minor portion of the other piece. The 95 rolled wearing edges are unstitched as in the other forms, and the ends of the cuff are inturned as seen at 19, see Figure 9, and then stitched as seen at 20 to give a finished appearance, the ends of the cuffs being free 100 from fastening means to connect them together, except by the stitches of button holes 105 21 which pass through the opposite faces of the cuff as seen clearly in Figure 9. It is to be understood that after the seams at 17 and 18 are formed the tubular member is turned 110 inside out so that the seams will be concealed within the cuff, the same as in the other forms, and as shown in Figure 8.

115 In some cases the opposite faces of the cuff may be secured together as by a short row of transverse stitches 22 as seen in Figures 8 and 9, in which case the stitches of the button holes need not extend through the opposite faces of the cuff. In some cases it 120 may be advisable to employ these transverse stitches in addition to the button holes to guard against strain on the button holes and to reinforce the material adjacent such button holes.

125 The form of cuff shown in Figures 8 and 9 can be reversed, that is worn with either side out, bringing the edge formed of the major portion of either piece into wearing position.

130 In all forms the joints between adjacent

edges of the material is such that the adjacent portions will in all cases be flush.

What is claimed as new is:—

1. A soft cuff the material of which is folded rolled and seamless at opposite edges of the cuff, the material being united between said edges, the cuff being provided with button-holes at the ends, the opposite faces of the cuff being connected together only at points between the folded edges, leaving the latter disconnected adjacent such edges.
2. A soft cuff formed of fabric in tubular form flattened with the opposite wearing edges rolled and seamless and having button-holes at the ends, the fabric being seamed between said edges, the button-hole stitches solely joining the opposite faces of the fabric at the ends.
3. A soft cuff formed of fabric of tubular form flattened, with a seam extending in the

direction of the length of the cuff and disposed between the rolled edges of the cuff, the ends of the fabric being inturned within the ends of the cuff, the cuff being provided at the ends with button-holes the stitches of which solely join the opposite faces of the fabric at the ends the rolled edges being free for movement.

4. A soft cuff formed of a single piece of material of flattened tubular form with the abutting edges thereof united by stitches, the ends of the material folded inward within the ends of the cuff, leaving the material at opposite sides rolled, the edges being unstitched, there being button holes in the end portions of the cuff, the stitches of which secure opposite portions of the material together, leaving the other portions disconnected from each other.

In testimony whereof I affix my signature.

ALBERT A. FOURNIER.
